[57] CLAIM

The ornamental design for an optical disk player, as shown and described.

DESCRIPTION

FIG. 1 is a perspective view of the top, front and right side of an optical disk player showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a perspective view similar to FIG. 1 with a disk receiving tray in an extended position.
